ROTARY PUMP

Harry L. Swan, Hot Springs, Ark.

Application December 5, 1933, Serial No. 701,033

9 Claims. (Cl. 103—136)

This invention relates to rotary pumps or compressors and while it is used efficiently for the purpose of forcing fluids, it is to be understood that with necessary modifications it can also be utilized as an efficient rotary engine of either the steam or internal combustion type.

Heretofore, in the construction of rotary pumps or the like it has been practically impossible to provide a perfect contact at all times between the stator and the rotor and this has been a very undesirable fault because of the leakage and resultant loss of power which has occurred.

It is an object of the present invention to provide the structure with a stator and a rotor so shaped as to permit the use of metal packing for maintaining tight connections between the piston heads and the stator.

It is a further object to so shape the stator and the rotor that the curvatures of the cooperating faces will remain constant and thereby eliminate any necessity of utilizing packing which must flex during the operation of the device in order to compensate for variations in curvatures.

It is a well known fact that no method of packing metal to metal surfaces is equal to that of the metal ring such as used upon engine pistons and the like. An object of the present invention is to provide a structure so shaped as to permit the use of packing substantially the same as that commonly employed.

A still further object is to provide a double acting mechanism whereby during the operation of the structure as a pump it will deliver an unbroken, non-fluctuating stream.

Another object is to provide a structure which, if used as a steam or other fluid engine, will operate under a constant and unvarying torque, the equivalent of one complete piston head being under constant pressure.

A still further object is to provide a structure of this character which, if used as an internal combustion engine, can produce three or more impulses per revolution of the rotor.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

In the accompanying drawings the preferred form of the invention has been shown.

In said drawings:

Figure 1 is a central horizontal section through the structure, a portion of one of the piston heads being shown partly in plan and partly in section.

Figure 2 is a reduced section on line 2—2, Figure 1.

Figure 3 is a vertical longitudinal section on a reduced scale, one of the piston heads being shown partly in elevation and partly in section.

Referring to the figures by characters of reference S designates a stator which is formed of

two opposed similar sections 1 and 2, the edge of each section being provided with an outstanding flange 3 whereby the sections can be held together by bolts 4 or the like extending through the flanges. Each section 1 and 2 constitutes a section of a sphere, said section being slightly less than a hemisphere so that when the sections are assembled as shown for example in Figure 2 they will cooperate to form a cavity 5 therebetween which is ellipsoidal in contour with its horizontal diameters equal, as will be apparent by referring to Figure 1 while the remaining diameters gradually shorten until they reach the vertical axis of the stator.

The two sections of the stator have oppositely extending bearing portions 6 which cooperate to house bushings in which are journalled the oppositely extending shafts 7 and 8 of a rotor 9. Shaft 8 can be a stub shaft seated in a bearing cup 10 forming one of the bushings and secured in any manner desired within one of the bearings 6 so as to provide a sealed connection. Shaft 7 can be journalled in a sleeve 11 constituting the other bushing and suitably packed as shown at 12 to prevent leakage.

The rotor 9 is ellipsoidal, its axis of rotation being coaxial with the long diameter of the rotor, and its curvature from shaft to shaft corresponding with the curvatures of those portions of the inner surface of the stator lying in a central vertical plane. Furthermore the short diameter of the rotor is substantially equal to the short diameter of the stator and as a result of these proportions the rotor 9 constantly maintains a working contact with the stator at the points 12 occupying a plane perpendicular to the meeting faces of the stator sections and extending axially of the rotor.

As the rotor is circular in transverse section and elliptical in longitudinal section and as the stator is circular in horizontal section but elliptical in vertical section, it will be obvious that concavo-convex chambers will be left between the rotor and stator, these chambers being oppositely disposed as indicated at 13 and 14 and being grad-

55

ually reduced in area toward the points of contact 12. Each space is provided with an intake 15 and an outlet 16 located adjacent to opposed extremities of the chamber and close to the 5 points of contact between the rotor and the stator.

Formed within the rotor are radial slots 17 extending in the direction of the axis of rotation and in each slot is slidably mounted a segmental piston head 18. The outer edge of each head is arcuate as indicated at 19 and is curved to correspond with the curvature of the interior of each stator section. Each piston head has a groove 20 in its arcuate edge providing a seat for a metal packing strip 21, the ends of the strip being extended into the rotor toward its axis of rotation. These packing strips are urged outwardly in any suitable manner, as by means of springs 22 located back of them and, consequently, the packing strips are maintained in contact with the inner surface of the stator so as to produce a tight working fit.

Springs 23 are preferably seated in registering bores 24 in the rotor and in the inner edge portions of the piston heads and these springs can be held against buckling by mounting them on pins 25 extending longitudinally of the bores.

For the purpose of maintaining tight connections between the rotor and stator at and adjacent to the points of contact 12, grooves 26 are formed in the rotor between the slots 17 and extend from shaft 7 to shaft 8. Each of these grooves is provided with a metal packing strip 27 similar to strips 21, said strip being packed by a spring 28 so as to be edged outwardly a limited distance.

Assuming that the structure herein described is to be used for forcing fluid, it will be apparent that fluid will be admitted to each chamber 13 or 40 14 through an intake 15. As a piston head 18 advances past the points of contact 12 and toward the intake 15 it will force in advance of it all fluid in the path thereof within compartment 14 and at the same time draw the fluid into the 45 space back of the piston head during the continued advance of said head. The fluid being forced forwardly by head 18 will be expelled through the outlet 16 of the compartment 14 and during this operation a similar action is taking place in the compartment 13. However by providing three 50 piston heads as shown the expelling actions from the two compartments will lap so that the resultant delivery of fluid will be continuous. As the strips 21 and 27 are of substantially the same curvature as the inner surfaces of sections 1 and 2, as will be apparent by referring to Figures 1 and 3, it will be obvious that the sealing action of the strips will be equal to that produced by a ring on a pump piston and it becomes unnecessary to provide seals adapted to flex in order to 55 compensate for wide variations in curvatures. On the contrary the wearing action upon all portions of the inner surface of the stator and throughout the length of each sealing strip will be uniform so that wear will be easily compensated for and a tight seal maintained under working conditions.

While the invention has been described and illustrated as a pump, it will be obvious as before explained, that the same features of construction can be embodied in a rotary engine, one side of the stator being used for compression and the other side for combustion in which event three impulses per revolution of the rotor would be obtained.

By utilizing an ellipsoidal rotor within an ellipsoidal stator all disadvantages heretofore incident to the proper sealing of a rotary pump or engine are eliminated, and it becomes possible to produce a structure of this character which is light, durable and compact in proportion to the power developed. 5

What is claimed is:

1. A stator comprising opposed sections each consisting of a sector of a sphere which is less than a hemisphere, said sections being joined to provide an ellipsoidal cavity, an ellipsoidal rotor in the stator having its axis of rotation coincident with its long diameter and at right angles to the short diameter of the cavity, said rotor contacting constantly with the stator at fixed diametrically opposed points to divide the cavity into non-communicating concavo-convex chambers, and piston heads carried by the rotor and slidable in planes extending longitudinally of its axis of rotation.

2. A stator comprising opposed sections each consisting of a sector of a sphere which is less than a hemisphere, said sections being joined to provide an ellipsoidal cavity, an ellipsoidal rotor 25 in the stator having its axis of rotation coincident with its long diameter and at right angles to the short diameter of the cavity, said rotor contacting constantly with the stator at fixed diametrically opposed points to divide the cavity into non-communicating concavo-convex chambers, and piston heads carried by the rotor and slidable in planes extending longitudinally of its axis of rotation, the diameter of the rotor in any plane perpendicular to its axis of rotation being substantially equal to that short diameter of the cavity in the same plane therewith.

3. A stator comprising opposed sections each consisting of a sector of a sphere which is less than a hemisphere, said sections being joined to 40 provide an ellipsoidal cavity, an ellipsoidal rotor in the stator having its axis of rotation coincident with its long diameter and at right angles to the short diameter of the cavity, said rotor contacting constantly with the stator at fixed diametrically opposed points to divide the cavity into non-communicating concavo-convex chambers, and piston heads carried by the rotor and slidable in planes extending longitudinally of its axis of rotation, the diameter of the rotor in any plane perpendicular to its axis of rotation being substantially equal to that short diameter of the cavity in the same plane therewith, the outer edge of each piston head being parallel with those faces of the cavity with which they cooperate. 55

4. A stator comprising opposed sections each consisting of a sector of a sphere which is less than a hemisphere, said sections being joined to provide an ellipsoidal cavity, an ellipsoidal rotor in the stator having its axis of rotation coincident with its long diameter and at right angles to the short diameter of the cavity, said rotor contacting constantly with the stator at fixed diametrically opposed points to divide the cavity into non-communicating concavo-convex chambers, and piston heads carried by the rotor and slidable in planes extending longitudinally of its axis of rotation, the diameter of the rotor in any plane perpendicular to its axis of rotation being substantially equal to that short diameter of the cavity in the same plane therewith, the outer edge of each piston head being parallel with those faces of the cavity with which they cooperate, and a metal packing strip carried by the outer edge of each piston head for constant working contact 70 75

with the wall of the cavity in a plane extending axially of the rotor.

5. A stator comprising opposed sections each consisting of a sector of a sphere which is less than a hemisphere, said sections being joined to provide an ellipsoidal cavity, an ellipsoidal rotor in the stator having its axis of rotation coincident with its long diameter and at right angles to the short diameter of the cavity, said rotor 10 contacting constantly with the stator at fixed diametrically opposed points to divide the cavity into non-communicating concavo-convex chambers, and piston heads carried by the rotor and slidable in planes extending longitudinally of 15 its axis of rotation, the diameter of the rotor in any plane perpendicular to its axis of rotation being substantially equal to that short diameter of the cavity in the same plane therewith, the outer edge of each piston head being parallel 20 with those faces of the cavity with which they cooperate, and a metal packing strip carried by the outer edge of each piston head for constant working contact with the wall of the cavity in a plane extending axially of the rotor, and metallic packing strips carried by the rotor between the piston heads for working contact with the 25 stator along opposed arcuate lines in planes extending axially of the rotor, thereby to divide the cavity into separate chambers separated by the rotor.

6. A device of the class described including an ellipsoidal rotor, a stator housing the rotor and comprising opposed spherical sections each of which is less than a hemisphere whereby, 30 when the sections are assembled, they contact throughout the length of their inner surfaces at fixed opposite points with the rotor in a plane extending axially of the rotor.

7. A device of the class described including an ellipsoidal rotor, a stator housing the rotor and comprising opposed spherical sections each of which is less than a hemisphere whereby, when 35 the sections are assembled, they contact

throughout the length of their inner surfaces at fixed opposite points with the rotor in a plane extending axially of the rotor thereby to produce opposed chambers between the rotor and stator separated by said points of contact between the rotor and stator, each chamber being concavo-convex.

8. A device of the class described including an ellipsoidal rotor, a stator housing the rotor consisting of opposed sections each consisting of a segment of a sphere which is less than hemispherical, said stator sections being circular in planes parallel with their contacting faces and being ellipsoidal in planes perpendicular to said contacting faces, the rotor being mounted 10 for rotation about its longitudinal axis in the plane of the meeting faces of the stator sections, said rotor and stator being proportioned for working contact along fixed opposed lines in a plane extending longitudinally of the axis of rotation and perpendicular to the contacting faces of the stator sections, and slidable piston heads carried by the rotor and having outer edges the 15 curvatures of which coincide with the curvature 20 of the inner surface of the stator in any plane 25 radiating from the axis of rotation.

9. A stator having a cavity elliptical in vertical section and circular in horizontal section, an ellipsoidal rotor therein rotatable about its long axis and having a constant working contact with 30 the wall of the stator at fixed diametrically opposed points thereby to divide the cavity into opposed non-communicating concavo-convex chambers, yieldingly pressed piston heads 35 slideable radially within the rotor and having their outer or free edges working close to and parallel at all times with the adjacent wall of the cavity, and packing strips carried by said edges and having a tight, wiping contact with the wall of the cavity thereby to divide each of said chambers into non-communicating high and low pressure sides.
